UNITED STATES PATENT OFFICE.

CYRUS S. OLDRYD, OF KNOXVILLE, TENNESSEE.

RAILWAY AND MEANS FOR LAYING THE SAME.

1,288,151.

Specification of Letters Patent.

Patented Dec. 17, 1918.

Application filed March 24, 1916, Serial No. 86,422. Renewed May 6, 1918. Serial No. 232,932.

To all whom it may concern:

Be it known that I, CYRUS S. OLDRYD, a citizen of the United States, residing at Knoxville, in the county of Knox and State 5 of Tennessee, have invented a new and useful Improvement in Railways and Means for Laying the Same, of which the following is a specification, reference being had to the accompanying drawing.

10 My improvement relates particularly to a railway track and means for laying said track, provision being made for extending the track endwise in accordance with the advancement of some operation performed 15 at or adjacent the end of the track, said operation being progressive relative to the track and requiring more and more extension of the track as such work progresses.

The object of the invention is to provide 20 means whereby such operation may be made relatively continuous, the periodical suspension of the operation for the laying of more track being made unnecessary.

The improvement is especially applicable 25 to tracks used in connection with mining and quarrying and excavating operations, the tracks being used for supporting and advancing machines used for such work, and the material to be removed being in 30 the way of extending an ordinary track at the level at which the machine approaches the mass or wall of material to be removed, and said machine being, preferably, used also for laying the extension of said track.

To this end, my improvement comprises ordinary rigid track rails and also articulated rails having their rear ends placed at the front of the rigid rails and adapted to be placed automatically and progressively while the machine supported by the track advances, so that in practice ordinary rigid rails may be laid as far as the bank or face or wall of material and the machine placed on said rails and put to work and then advanced, while and as fast as the work proceeds, upon the articulated rails, these rails laying themselves into position synchronously with the advance of the machine, and so continuing until the entire length of the articulated rails has been laid. Then the machine is moved backward until it again rests entirely on the rigid rails. Then the articulated rails are detached and a length or lengths of rigid rails substituted. Then the articulated rails are put into position at the new end of the rigid rail track

to be again paid out when the machine moves forward and leaves the forward ends of the ordinary rigid rails last put into position. The unlaid portions of the articulated rails 60 are preferably supported by and paid out by said machine as it advances, so that said machine is a mining or excavating or similar machine and is also a track laying machine.

65

In the accompanying drawings,

Figure 1 is a side elevation showing a portion of a mining machine and a track embodying my improvement;

Fig. 2 is an elevation of a common section 70 of one of the articulated rails;

Fig. 3 is a plan of the same section, a portion of another section being applied thereto;

Fig. 4 is a plan of the rear section of one 75 of the articulated rails, attached to an ordinary rigid rail, and having a portion of a common articulated rail attached;

Fig. 5 is a horizontal section on the line, 80 5-5, of Fig. 1;

Fig. 6 is a front elevation of the right hand front wheel of the machine resting on the front end of the articulated rail;

Fig. 7 is a section on the line, 7-7, of Fig. 1, looking in the direction of the arrow, 85 portions being broken away.

Referring to said drawings, A is the machine having an axle, A¹, and wheels, A², in the form of ordinary car wheels, usually having a flange, A³, and a tread, A⁴, (only 90 one of said wheels being shown). Two rigid rails, B, of ordinary form and having the usual head, B¹, web, B², and foot, B³, are placed parallel to each other and joined by ties, B⁴. In the form shown in the drawings, these ties are flat metal plates lying beneath the rails and having their ends formed to engage the rails.

C, C, are the articulated rails. Each of these rails is composed of a series of sections, C¹, of the form illustrated separately in Figs. 2 and 3. Each of said sections has two outer extensions, C², and an inner extension, C³, all of said extensions being parallel to the length of rail and the outer 105 extensions being spaced from each other the proper distance to receive between them the inner extension, C³, of the next adjoining section. A horizontal shaft or pintle, C⁴, extends transversely and loosely through adjacent extensions, C² and C³. In this manner these sections are articulated to each 110

other so as to permit the rail to conform to the curvature of the wheels, A², of the machine A.

Each section, C¹, has a lateral extension, 5 C⁵, in the upper face of which is a longitudinal curve, C⁶, of proper form to receive the flange, A³, of the wheel, A², to control the positioning of the articulated rails as hereinafter described. Said extensions also 10 serve to increase the base area of said sections, whereby the articulated rails are more firmly seated on the floor.

The height of each section, C, is shown to be equal to the height of the rails, B, 15 plus the thickness of the tie, B⁴, in order that the articulated rails may rest upon the same floor level as the tie does and at the same time have their upper faces reach the level of the upper face of the rails, B.

20 The extensions, C² and C³, on the sections C¹, may be extended either forward or backward. In other words, either end of the sections, C¹, may be directed either forward or backward. This permits reversing the 25 articulated rails as may be necessary to bring the lateral extensions, C⁵, beneath the flanges, A³, of the wheels. Because these sections are thus reversible and interchangeable, they may be termed "common" sections 30 to distinguish them from the coupling sections which are next described.

At the junction of the articulated rails and the rigid rails, a modified form of section, C¹, is used. For convenience, these 35 are termed, "coupling sections." These two sections are made right and left. Each has at its rear end an opening, C⁸, to receive the forward end of the adjacent rigid rail. B. At the outer side of said section, a set-bolt, 40 C⁹, extends horizontally through said section and bears against the web, B², of the rigid rail, whereby said section and said rail are bound to each other.

At the inner side of said section is an extension, C⁵, in the upper face of which is a groove, C⁶, like the groove, C⁶, in the section, C¹. At the forward end, one of these sections has two outer extensions, C², while the other of said extensions has at its forward 45 end an inner extension, C⁸.

On the machine, A, above each rigid rail B, and above the upper portion of the wheels, A², is a trough, A⁵, in which the adjacent articulated rail may lie after extending upward from the front end of the rigid rail along the front portion of the front wheel, A². Said trough constitutes a holder or place of storage for the surplus portion of the articulated rail when the latter is attached preparatory to forward movement of the machine thereon.

When the articulated rails have been thus applied preparatory to said movement thereon, the flanges, A³, of the forward 55 wheels, A², extend into the groove, C⁶, of

all the sections, C¹, which at the time bear against the tread of the wheel, and as the wheel advances, the flange enters the groove of each succeeding section, C¹, with which the wheel is brought into engagement. By 70 means of this engagement between the wheel flange and the sections, C¹, the articulated rail is positioned to conform to the gage of the track of which the rigid rails, B, B, form a part.

When the machine has advanced far enough upon the articulated rails to call 75 for the insertion of additional rigid rails, the machine is moved backward and the articulated rails put into position in the 80 troughs, A⁵. When the rigid rails have been put into place, the machine is again moved forward nearly to the forward ends of the rigid rails. Then the articulated rails are again secured to the rigid rails; after which 85 the machine may again move forward on the articulated rails.

In lieu of the set bolt, C⁹, shown in Figs. 1 and 5, cam levers, L, are shown in Figs. 4 and 7 as applied to the coupling sections 90 for bearing against the web, B², of the common rail for clamping the coupling sections to the common rail.

The machine, A, constitutes a vehicle to travel on the rails and to carry the articulated rails prior to their laying.

I claim as my invention,

1. In an apparatus of the nature described, rigid rails lying parallel to each other, means for securing said rails, and articulated rails adapted to have their rear ends applied at the forward ends of the rigid rails and to be progressively laid for receiving the wheels of a vehicle, substantially as described.

2. In an apparatus of the nature described, rigid rails lying parallel to each other, means for securing said rails, and articulated rails adapted to have their rear ends applied at the forward ends of the rigid rails, and a vehicle for carrying and progressively laying and traveling upon said articulated rails, substantially as described.

3. In an apparatus of the nature described, rigid rails lying parallel to each other, means for securing said rails, and articulated rails detachably secured by their rear ends to the forward ends of the rigid rails, and adapted to fold against the forward portions of wheels on said articulated rails, substantially as described.

4. In an apparatus of the nature described, rigid rails lying parallel to each other, means for securing said rails, articulated rails adapted to be detachably secured by their rear ends to the forward ends of the rigid rails, and a vehicle for carrying and laying and traveling upon said articulated rails, substantially as described.

5. In an apparatus of the nature described, rigid rails lying parallel to each other, means for securing said rails, articulated rails adapted to be detachably secured by their rear ends to the forward ends of the rigid rails, and a vehicle for carrying and laying and traveling upon said articulated rails, the sections of said articulated rails having grooves to receive wheel flanges, substantially as described.
6. In an apparatus of the nature described, rigid rails lying parallel to each other, means for securing said rails, and articulated rails adapted to have their rear ends applied at the forward ends of the rigid rails and to be progressively laid for receiving the wheels of a vehicle, the sections of said articulated rails having grooves to receive wheel flanges, substantially as described.
7. In an apparatus of the nature described, rigid rails lying parallel to each other, means for securing said rails, and articulated rails adapted to have their rear ends applied at the forward ends of the rigid rails, and a vehicle for carrying and progressively laying and traveling upon said articulated rails, the sections of said articulated rails having grooves to receive wheel flanges, substantially as described.
8. In an apparatus of the nature described, rigid rails lying parallel to each other, means for securing said rails, and articulated rails detachably secured by their rear ends to the forward ends of the rigid rails, and adapted to fold against the forward portions of wheels on said rails, the sections of said articulated rails having grooves to receive wheel flanges, substantially as described.
9. In an apparatus of the nature described, rigid rails lying parallel to each other, means for securing said rails, and articulated rails adapted to have their rear ends applied at the forward ends of the rigid rails and to be progressively laid for receiving the wheels of a vehicle, the sections of the articulated rails having lateral extensions in which are grooves for receiving wheel flanges, substantially as described.
10. In an apparatus of the nature described, rigid rails lying parallel to each other, means for securing said rails, and articulated rails adapted to have their rear ends applied at the forward ends of the rigid rails, and a vehicle for carrying and progressively laying and traveling upon said articulated rails, the sections of the articulated rails having lateral extensions in which are grooves for receiving wheel flanges, substantially as described.
11. In an apparatus of the nature described, rigid rails lying parallel to each other, means for securing said rails, and articulated rails detachably secured by their rear ends to the forward ends of the rigid rails, and a vehicle for carrying and laying and traveling upon said articulated rails, said articulated rails comprising rear sections having their rear ends formed for coupling to rigid rails and having their forward ends formed for receiving wheel flanges, substantially as described.
12. In an apparatus of the nature described, rigid rails lying parallel to each other, means for securing said rails, articulated rails adapted to be detachably secured by their ends to the forward ends of the rigid rails, and a vehicle for carrying and laying and traveling upon said articulated rails, the sections of the articulated rails having lateral extensions in which are grooves for receiving wheel flanges, substantially as described.
13. In an apparatus of the nature described, rigid rails lying parallel to each other, means for securing said rails, and articulated rails adapted to have their rear ends applied at the forward ends of the rigid rails and to be progressively laid for receiving the wheels of a vehicle, said articulated rails comprising rear sections having their rear ends formed for coupling to rigid rails and having their forward ends formed for coupling to other sections of said articulated rails, substantially as described.
14. In an apparatus of the nature described, rigid rails lying parallel to each other, means for securing said rails, and articulated rails adapted to have their rear ends applied at the forward ends of the rigid rails, and a vehicle for carrying and progressively laying and traveling upon said articulated rails, said articulated rails comprising rear sections having their rear ends formed for coupling to rigid rails and having their forward ends formed for coupling to other sections of said articulated rails, substantially as described.
15. In an apparatus of the nature described, rigid rails lying parallel to each other, means for securing said rails, and articulated rails detachably secured by their rear ends to the forward ends of the rigid rails, and adapted to fold against the forward portions of wheels on said rails, said articulated rails comprising rear sections having their rear ends formed for coupling to rigid rails and having their forward ends formed for coupling to other sections of said articulated rails, substantially as described.
16. In an apparatus of the nature described, rigid rails lying parallel to each other, means for securing said rails, articulated rails adapted to be detachably secured by their rear ends to the forward ends of the rigid rails, and a vehicle for carrying and laying and traveling upon said articulated rails, said articulated rails comprising rear sections having their rear ends formed

for coupling to rigid rails and having their forward ends formed for coupling to other sections of said articulated rails, substantially as described.

17. In an apparatus of the nature described, rigid rails lying parallel to each other, means for securing said rails, and articulated rails adapted to have their rear ends applied at the forward ends of the rigid rails and to be progressively laid for receiving the wheels of a vehicle, said articulated rails comprising rear sections having their rear ends formed for coupling to rigid rails and having their forward ends formed for coupling to the other sections of said articulated rails, and members on said rear sections for binding said sections to the fixed rails, substantially as described.

18. In an apparatus of the nature described, rigid rails lying parallel to each other, means for securing said rails, and articulated rails adapted to have their rear ends applied at the forward ends of the rigid rails, and a vehicle for carrying and progressively laying and traveling upon said articulated rails, said articulated rails comprising rear sections having their rear ends formed for coupling to rigid rails and having their forward ends formed for coupling to the other sections of said articulated rails, and members on said rear sections for binding said sections to the fixed rails, substantially as described.

19. In an apparatus of the nature described, rigid rails lying parallel to each other, means for securing said rails, and articulated rails detachably secured by their rear ends to the forward ends of the rigid rails, and adapted to fold against the forward portions of wheels on said rails, said articulated rails comprising rear sections having their rear ends formed for coupling to rigid rails and having their forward ends formed for coupling to the other sections of

said articulated rails, and members on said rear sections for binding said sections to the fixed rails, substantially as described.

20. In an apparatus of the nature described, rigid rails lying parallel to each other, means for securing said rails, articulated rails adapted to be detachably secured by their rear ends to the forward ends of the rigid rails, and a vehicle for carrying and laying and traveling upon said articulated rails, said articulated rails comprising rear sections having their rear ends formed for coupling to rigid rails and having their forward ends formed for coupling to the other sections of said articulated rails, and members on said rear sections for binding said sections to the fixed rails, substantially as described.

21. In an apparatus of the nature described, a vehicle having wheels adapted to travel upon rails and having supports upon which articulated rail sections may rest and slide, and articulated rail sections upon which said wheels may travel and adapted to rest and slide upon said supports and having their rear ends adapted to rest upon the ground while other portions of said rails are paid out progressively over the forward wheels of the vehicle until the forward ends of said rails rest upon the ground, substantially as described.

22. In an apparatus of the nature described, parallel fixed rails, articulated rails having their rear ends secured at and in alinement with the fixed rails, and a vehicle having wheels resting upon said rails and supporting portions of the articulated rails in position to be paid upon the floor by the forward movement of said vehicle, substantially as described.

In testimony whereof I have signed my name, this 23rd day of March, in the year one thousand nine hundred and sixteen.

CYRUS S. OLDROYD.
